SHUTTLELESS LOOM WHICH PNEUMATICALLY PROJECTS WEFT THREAD

George W. Dunham, Westport, Conn.

Application December 24, 1948, Serial No. 67,134

13 Claims. (Cl. 139—127)

1

The invention relates to so-called shuttleless looms, and more particularly to a loom in which each pick of weft thread is carried through the shed by an air blast.

An object of the present invention is to provide a shuttleless loom of the above character which is relatively simply in construction, which is faster, and which has greater freedom from shut-downs than conventional shuttle type looms.

According to a preferred embodiment of the invention, the lay beam of the loom is provided with a pneumatic jet projector at one end and a suction tube at the other end. The jet projector comprises an outer tube within which is a hollow needle. A suitable annular chamber connects with the space between the hollow needle and the outer tube to which a steady stream of compressed air is fed. The weft thread passes through the hollow needle, straight through the jet projector.

According to a preferred form of the invention, the weft thread is controlled by a metering device which may be mounted on a stationary part of the machine adjacent the lay beam. This metering device comprises a continuously rotating measuring wheel against which is pressed, at times, a presser wheel. The weft thread passes over the presser wheel and through a suitable braking device for arresting movement of the weft thread. When the presser wheel engages the measuring wheel, the brake is released to feed weft thread to the jet projector; and when the presser wheel disengages the measuring wheel, the brake is applied to stop the feed of the weft thread.

According to the said preferred embodiment, the presser wheel and brake movement is conveniently controlled by a control arm having a finger engaging in the notch of a one-revolution collar. The one-revolution collar is mounted on a stud shaft and driven by a gear, also mounted on said shaft, through a suitable friction clutch. The said gear engages with a pinion on the measuring wheel shaft which is power driven; the gear ratio is such that the measuring wheel makes a predetermined number of revolutions while the one-revolution collar makes one revolution. The number of revolutions made by the measuring wheel, while the presser wheel is in engagement therewith, corresponds to the width of the cloth.

When the finger is in the notch of the one-revolution collar, the weft brake is applied and no weft thread is projected. Operation of the control lever removes the finger from the notch, releasing the one-revolution collar permitting it

2

to make one revolution. The disengagement of finger and notch causes the presser wheel to engage the measuring wheel and the brake to release. The control lever may be conveniently operated by a latch arrangement, controlled by an electric solenoid; the solenoid is in turn controlled by an electric switch on one of the shafts of the machine; this times the projection of the weft thread to that part of the weaving cycle in which the shed is open.

The invention also consists in certain new and original features and combinations hereinafter set forth and claimed.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part hereof, in which:

Fig. 1 is an end elevation of a simple loom to which the invention is applied;

Fig. 2 is a cross section on the line 2—2 of Fig. 1, showing the cam-operated timing switch;

Fig. 3 is a somewhat diagrammatic, longitudinal, vertical section taken on the line 3—3 of Fig. 1;

Fig. 4 is a detail elevation of the weft thread measuring device, the parts being shown in position holding the weft thread stationary;

Fig. 5 is a view similar to Fig. 4 but showing the parts in position for feeding and measuring the weft thread;

Fig. 6 is a detail on the line 6—6 of Fig. 4 showing the separate drive motor for the weft thread measuring device;

Fig. 7 is a section on the line 7—7 of Fig. 5 illustrating the one-revolution collar and drive therefor;

Fig. 8 is a longitudinal section taken through the feed jet, and

Fig. 9 is a transverse section taken on the line 9—9 of Fig. 8.

In the following description and in the claims, various details will be identified by specific means for convenience, but they are intended to be as generic in their application as the art will permit.

Like reference characters denote like parts in the several figures of the drawings.

In the drawings accompanying and forming part of this specification, certain specific disclosure of the invention is made for purposes of explanation, but it will be understood that the

details may be modified in various respects without departure from the broad aspect of the invention.

Referring now to the drawings, and more particularly to Figs. 1 to 3, a conventional type loom is shown to which the invention is applied. Conventional parts of the loom are shown somewhat diagrammatically and a simple form of loom is shown for purposes of simplicity. It will be understood that the invention is directed mainly to the pneumatic weft feeding and tensioning arrangement, to the weft thread metering arrangement and to the manner in which these arrangements are incorporated into the loom.

The loom comprises, in general, a suitable framework indicated by 10; warp beam 11, from which the warp threads are fed in the direction of the arrow X; tension rods 12; harness 14 comprising frames A and B operating the shed 13; lay beam 15 carrying reeds 16; breast beam 17 over which the finished cloth passes; and the roll 18 of finished cloth.

The weft projecting devices comprises in general the projecting nozzle or jet projector 19, the suction tube 20 and the thread metering device (see particularly measuring wheel 21 and presser wheel 22).

All of these parts will be described more in detail hereinafter.

The warp beam 11 is suitably journaled in frame 10 and has the warp thread wound thereon as is well known. Any suitable means may be provided for driving or letting off the warp beam.

The warp threads are divided into groups *a* and *b* passing over and under the tension rods 12 to form the shed 13. The shed is opened and closed by the harness 14 which comprises frames A and B. It will be understood that, when one frame A is up, as shown in Figure 3, the other frame B is down and that the positions of these frames reverses, as is well known in the art.

The harness 14 is driven from main shaft 25 suitably journaled in the main frame 10 of the machine. Shaft 25 is driven continuously by a suitable motor or other source of power (not shown). Main shaft 25 drives harness shaft 27 through gears 26 in a two-to-one relationship; the main shaft makes two revolutions for every one revolution of the harness shaft.

Harness shaft 27 has cams 28 operating on reciprocating treadles 30 suitably pivoted to the frame of the machine. Treadles 30 operate upon members 33 which in turn are connected to transverse lower bars 32 forming part of the harness frames A and B. Straps 34 pass over pulleys 35 and connect the upper bars 31 of harness frames A and B. Pulleys 35 are mounted on shaft 36 journaled in the frame of the machine.

It will be understood that warp threads *a* are controlled by frame A and warp threads *b* are controlled by frame B. Thus, as harness drive shaft 27 rotates, the treadles 30 reciprocate harness frames A and B up and down, opening and closing the shed 13, as is well known to those skilled in the art.

The lay beam 15 is mounted on swords 40 suitably mounted on pivot shaft 41 journaled in the machine frame. The lay beam 15 carries reed frame 42 having the reeds 16. Main drive shaft 25 has cranks 37 on which are journaled connecting rods 38 pivoted to the lay beam 15. It will be understood that rotation of drive shaft 25 causes the lay beam 15 to move to the right in Fig. 3 causing the reed 16 to beat the weft

thread into the cloth and then to return to the position shown, as is well known.

The breast beam 17 extends all the way across the machine and supports, on one side, the stationary jaw 43 of weft thread cut off shears. A movable jaw 44 is pivoted to stationary jaw 43, and a spring 45 normally holds the jaw 44 in open position. Movable jaw 44 has an arm 46 against which lay beam 15 strikes to close the shears to cut the weft thread, as explained hereinafter. A similar cut-off shears (not shown) may be mounted on the breast beam at the other side of the loom, and similarly operated, if desired, to trim off the other end of the weft thread.

The cloth roll 18 is suitably journaled in the frame of the machine and may be driven to wind up the finished cloth in any convenient or well known manner.

The suction tube 20 of the weft projecting devices has a flared mouth 52 and is suitably clamped to the lay beam 15. A flexible pipe 50 extends to a suitable suction pump (not shown) which may be mounted in some convenient stationary position.

The pressure nozzle or jet projector 19 is also mounted on the lay beam 15 in line with the suction tube 20. It, too, has a flexible pipe 51 connecting with a suitable source (not shown) of compressed air which may be a standard air compressor mounted in some convenient stationary position.

Referring to Figs. 8 and 9, the projecting nozzle or jet projector 19 will now be described. It comprises a main tube 52 connecting with an inner chamber 53. An annular chamber 54 surrounds inner chamber 53 connecting therewith by a series of radial holes 59. The annular chamber 54 is closed by a band 55 suitably secured to the walls of annular chamber 54. A nipple 56 is welded to band 55 and is connected to flexible pipe 51 for supplying the jet 19 with compressed air.

Disposed within tube 52 is hollow needle 57. Needle 57 has a base 58 connected to the walls of annular chamber 54 by screws 62. The hollow needle 57 has a rounded surface 60 and the bore of tube 52 has a rounded surface 61 to facilitate flow of air around the annular throat between the hollow needle 57 and the tube 52. The weft thread W passes through the hollow needle in the direction of the arrow in Fig. 8.

When compressed air is supplied to nipple 56, the annular chamber 54 carries the air uniformly around the entire circumference of the chamber; thence the air passes inwardly through the holes 59 into the inner annular space 53 whence the air passes through the annular throat between the hollow needle 57 and feed tube 52. The compressed air issuing out of the mouth of the nozzle carries the thread W along with it, projecting the thread through the shed across the width of the loom as described hereinafter.

Referring now more particularly to Figs. 4 to 7, the weft thread metering device will now be described. This device is mounted upon a separate frame 66 attached to the main frame 10 of the machine and does not move with the lay beam 15. It comprises an electric motor 67 on whose shaft 72 is mounted the measuring wheel 21; wheel 21 is secured to shaft 72 by set screw 69. Rigidly mounted on the hub of measuring wheel 21 is pinion 68, being secured thereto by set screw 70. A rubber band or tire 71 encircles measuring wheel 21.

Pinion 68 drives large gear 73. Large gear 73

is loose on stud shaft 74 secured to frame 66. Gear 73 is secured to flange 79 of sleeve 75 by bolts as indicated in Fig. 7; sleeve 75 is journaled on shaft 74. Sleeve 75 is held axially in position between the shoulder 78 on shaft 74 and washer 84 held in position by cotter pin 85.

One-revolution collar 76 is journaled on sleeve 75. On either side of collar 76 is a friction clutch washer 81. A helical spring 82, retained by washer 83 sprung in a groove in sleeve 75, abuts one of the clutch washers 81, axially urging one-revolution collar 76 against the other friction washer 81 which in turn presses against hub of gear 73; the construction is such that, in effect, large gear 73 drives one-revolution collar 76 through a friction slip clutch. The friction clutch washer 81 adjacent spring 82 is feather keyed to sleeve 75 by a pin 86 set into the sleeve, as shown in Fig. 7, to prevent rotation of the washer from winding up the spring.

The one-revolution collar 76 is held stationary by a control lever 86 having a finger 88 engaging in collar notch 77. It will be understood that even though one-revolution collar 76 is held stationary, the drive gear 73 rotates continuously, the friction clutch washers 81 permitting such action. However, when finger 88 is removed from notch 77, the friction clutch drives one-revolution collar 76, causing it to make one revolution when finger 88 again drops into notch 77; during the one revolution, finger 88 rides on the periphery of collar 76.

Control lever 86 is made up of members 87 and 88 suitably riveted together. Member 87 is pivoted to frame 66 at 83. Member 88 has an offset foot 91 engaging a helical spring 92 which also engages a fixed abutment 93. It will be understood that spring 92 normally urges finger 88 into engagement with notch 77.

Control lever member 87 has a flexible brake shoe 96 bearing upon a smooth surface brake rod 97 suitably secured to an adjustable plate 98. This plate has slots through which screws 99 pass securing it to frame 66 to permit vertical adjustment of rod 97 to get proper brake pressure against brake shoe 96. It will be understood that the thread W passes over brake rod 97, between rod 97 and brake shoe 96, and is clamped between these two members when they are in the position shown in Fig. 4.

Presser wheel 22 is journaled on arm 100 which is pivoted to frame 66 at 101. The position of arm 100 is controlled by an extension 102 engaging foot 91 and engaging a helical spring 103 seated in a cup 104 secured to control lever member 87. It will be understood that the spring 103 acts to move presser wheel 22 toward measuring wheel 21 and to yieldably hold presser wheel 22 against measuring wheel 21 when finger 88 is disengaged from notch 77 (see Fig. 5).

The position of control lever 86 is controlled by a solenoid and latch engagement which will now be described. A solenoid 104 is mounted upon a bracket secured to frame 66. It has a movable plunger 105 to which is pivoted a latch 106 by pivot 107. Latch 106 engages a stop 108 secured to frame 66. A tension spring 109 operates between stop 108 and a projection 110 on latch 106 to hold the latch in engagement with stop 108 and in engagement over the end of control lever member 86 when in the position shown in Fig. 4.

The path of the weft thread W will now be described. The weft thread is stored in a suitable package or cone 114 mounted on the main frame of the machine (see Fig. 1). Thread W

passes through guides 116 and 117, thence between brake surfaces 96, 97, thence between the rubber tire 71 of measuring wheel 21 and the smooth surface of presser roll 22 (see Fig. 6). The thread W then passes through guide 121 into the back of jet 19 where it passes straight through the jet, as illustrated particularly in Fig. 8.

The solenoid 104 is controlled by a control circuit shown in Fig. 1. A switch 119 is mounted on the frame 10. The switch has a pushbutton controlled by cam 118 mounted on main shaft 25. As the projection on cam 118 engages the pushbutton of switch 119, it closes the switch. Wires indicated by 120 connect switch 119 and solenoid 104 with a source of electric power as indicated. Thus, every time cam 118 closes switch 119, solenoid 104 is operated and held operated until the projection on the cam 118 rides off the pushbutton when the switch 119 opens and solenoid 104 releases.

Operation

The loom operates as follows. Compressed air is applied continuously to hose 51 and suction is applied continuously to hose 50. The weft thread W is held by brake 96, 97 and the presser wheel 22 is in released position as shown in Fig. 4, when the shed is closed, thus preventing the weft thread W from being projected across the loom. When the shed opens, the brake 96, 97 releases and the presser wheel 22 engages continuously rotating measuring wheel 21, permitting a predetermined length of weft thread to be projected through the shed across the loom.

It will be understood that the shed 13 opens and closes in accordance with the movement of the harness under control of harness shaft 27. In the position shown in Fig. 3, the shed is open; the weft thread has been projected through the shed; and the lay beam 15 is in substantially its backmost position. The lay beam 15 is about to move forward. The projected weft thread is held taut, anterior of the reed 16, by the jet 19 and by the suction tube 20. As the lay beam 15 moves forward, the reed 16 beats this weft thread into the cloth; and as the lay beam 15 engages shear arm 46, shears 43, 44 sever the weft thread adjacent the jet 19.

In the meantime, the shed is closing and opening in the opposite direction. As the lay beam 15 nears its rearmost position, the projection on timing cam 118 closes switch 119 which operates solenoid 104. This pulls control lever 86 clockwise (see Fig. 4), disengaging finger 88 from notch 77; this releases one-revolution collar 76, permitting it to make one revolution, the finger 88 riding on the periphery of the one-revolution collar, holding control lever 86 to the right for a complete revolution.

Clockwise movement of control lever 86 releases brake 96, 97 and presses presser wheel 22 against measuring wheel 21 as illustrated in Fig. 5. The jet nozzle 19 exerts continuous pull on the weft thread W. The engagement of presser wheel 22 with feed wheel 21 draws weft thread from package 114 and positively feeds the thread to the jet nozzle 19 which projects the thread through the shed.

It will be understood that the gear ratio between gears 68 and 73 is such that, when one-revolution collar 76 is making one revolution, measuring wheel 21 will make a sufficient number of revolutions to measure the proper amount of weft thread equivalent to the width of the cloth being woven.

When the proper amount of weft thread W is paid out, the control finger 88 drops again down into notch 77 under pressure of spring 92. This releases presser wheel 22 from measuring wheel 21 and causes brake shoe 96 to press thread W against pin 97, stopping further feed of weft thread.

When the solenoid 104 operates and pulls finger 88 out of notch 77, a tip projection 111 on the latch 106 engages the solenoid frame raising the latch 106 about its pivot 110 causing it to disengage member 90.

The parts of this operating mechanism are so arranged that finger 88 is free to drop back into notch 77, under pressure of spring 92, regardless of the length of time solenoid 104 remains actuated. If notch 77 comes into register with finger 88 before solenoid 104 releases, the finger is free to drop into notch 77 as clearly indicated in Fig. 5; upon release of solenoid 104, the cam surface 122 on latch 106 will then ride up on member 90 and drop down with the catch shoulder 123 behind member 90 to the position shown in Fig. 4. On the other hand, if solenoid 104 releases before notch 77 comes into register with finger 88, spring 107 pulls latch 106 back into position against stop 108, causing the latch to ride over the end of member 90 and take such a position against stop 108 as to permit member 90 to move into position behind catch shoulder 123 when notch 77 comes into register with finger 88.

Tests have shown that the weft thread is projected instantly through the shed with great speed and accuracy. The thread is measured as it is fed and when the correct amount is paid out, further projection is prevented by the thread brake. As the weft thread travels into the neighborhood of the suction nozzle, the suction takes hold and holds the weft thread under tension and the thread is measured while it is so held. The forward movement of the lay beam causes the reed to beat the thread into the cloth and cuts off the weft thread as the shed closes. As the velocity of the projected weft thread is very high, it need not be projected until the shed is substantially wide open.

The weft thread may be measured to overhang slightly the edge of the cloth at either side. In place of the usual selvage, if desired, the cloth may be run through a suitable hardenable liquid which will cement or secure the warp and weft threads together at the side margins of the cloth to prevent any unraveling which might otherwise occur due to handling the cloth before making up into clothing or other manufactured goods. The short loose ends of the weft may be tucked back into the warp by any suitable means (not shown) at a succeeding opening of the shed.

By varying the speed and diameter of the measuring wheel, any reasonable weft thread velocity may be obtained. By varying the gear ratio between gears 68 and 73, any thread length corresponding to any width of cloth is obtainable, within the limitations of the weft projecting device. The rubber surface of the measuring wheel 21 is such as to give good traction to the thread. The surface of the brake pin 97 is such as to allow the thread to slip freely with brake released and to grip the thread instantly when the brake is applied. Presser wheel 22 is made as free running as possible so that it may continue to spin between successive projections of successive weft threads; it is made as light in weight as possible so it may accelerate quickly

to catch up with the measuring wheel when coming into contact with it. The weft thread is thus accelerated and decelerated almost instantly.

It will be understood that the timing of the weft projections may be tied to other parts of the loom; also that in practice, other parts of the loom, shown diagrammatically, will be suitably counterbalanced and otherwise arranged for the faster loom speeds made possible by the present invention.

It will be noted that the metering device measures as it feeds the weft thread into the jet projector. The weft thread is not completely measured until it is projected the entire width of the loom and is caught by the suction tube. At this time the presser wheel disengages the measuring wheel and the brake elements grip the weft thread stopping further feeding thereof. In other words, the weft thread metering device not only measures the thread but controls both the starting and stopping of the projection thereof. The air pressure on the jet projector and the suction on the suction tube is continuous and are continuously available to carry the weft thread through the shed and to hold it taut under control of the metering device.

The relationship of the metering wheels and the lay beam is such that the comparatively small movement of the lay beam does not interfere substantially with the length of thread extending from the metering wheels to the jet projector. At the time of weft projection, the jet projector is preferably in line with the metering guide 121 but this relationship is not especially critical.

An example of specifications of the weft projecting and metering apparatus will now be given. In tests, a 40/1 weft thread was projected a distance of 44 to 48 inches from the projecting nozzle. Peripheral speed of the measuring wheel 21 was 31 feet per second, this being also the speed of travel of the weft thread across the loom. The jet projector had the following dimensions. The inner bore of the tube 52 was $\frac{1}{8}$ inch in diameter, its overall length $1\frac{1}{4}$ inches. The overall length of the hollow needle was $1\frac{1}{2}$ inches, and the diameter of the hole through the hollow needle was .055 inch. The pressure of the compressed air fed to the jet projector was 7 pounds gauge. The $1\frac{1}{2}$ inch inside diameter suction nozzle had a flaring mouth about $\frac{1}{2}$ inch larger and the suction pressure was $2\frac{1}{4}$ inches of water $1\frac{1}{4}$ inches from the open end.

While certain novel features of the invention have been disclosed herein, and are pointed out in the annexed claims, it will be understood that various omissions, substitutions and changes may be made by those skilled in the art without departing from the spirit of the invention.

What is claimed is:

1. In a loom, mechanism to form a shed, a jet projector at one end of said shed, a suction tube at the other end of said shed, means for supplying substantially constant pressure to said jet projector, means for supplying substantially constant suction to said suction tube, a weft metering device comprising a continuously rotating measuring wheel, a presser member intermittently pressing against said measuring wheel, means for guiding weft thread between said measuring wheel and presser member and into said jet projector, means synchronized with the loom for urging said presser member and measuring wheel together at a time when the shed is open, and for holding said member and wheel together until

a predetermined length of thread is fed to said jet projector.

2. In a loom, mechanism to form a shed, a jet projector at one end of said shed, a suction tube at the other end of said shed, means for supplying substantially constant pressure to said jet projector, means for supplying substantially constant suction to said suction tube, a weft metering device comprising a continuously rotating measuring wheel, a presser wheel intermittently pressing against said measuring wheel, means for guiding weft thread between said measuring and presser wheels and into said jet nozzle, means synchronized with the loom for urging said presser and measuring wheels together at a time when the shed is open, a timing control for separating said wheels, said timing control being operated by rotation of a predetermined number of revolutions of said measuring wheel beginning with initial contact of said wheels, whereby said jet projector projects the weft thread through said shed as the weft thread is measured by said measuring wheel.

3. In a loom, means for forming a shed, a device for projecting a weft thread through the shed, a metering device for feeding predetermined lengths of weft thread through the shed, said metering device comprising a continuously moving measuring wheel, a presser member, a control cam, a lever system having a finger engageable with said cam, said lever system operating to press said wheel and member together at times, gearing between said measuring wheel and said cam to cause said measuring wheel to make a predetermined number of revolutions corresponding to the width of the cloth while said cam makes a predetermined movement, said wheel and member being separated while said finger engages one part of said cam, said wheel and member being pressed together while said finger engages another part of said cam.

4. In a loom, means for forming a shed, a device for projecting a weft thread through the shed, a metering device for feeding predetermined lengths of weft thread to the projecting device, said metering device comprising a continuously moving, measuring wheel, a presser wheel adapted to engage said measuring wheel, a thread brake adjacent said wheels, a timing collar having a notch, a lever system having a finger engageable in said notch at times and rideable on the periphery of said collar at times, said lever system operating said brake and said presser wheel, gearing between said measuring wheel and said timing collar to cause said measuring wheel to make a predetermined number of revolutions, corresponding to the width of the cloth, while said collar rotates a predetermined angle, the arrangement being such that said wheels are separated and said brake is applied to the thread while said finger is engaged in said notch, and said wheels are pressed together and said brake is released while said finger rides on the periphery of said collar.

5. In a loom, a projecting jet for projecting weft threads across the loom, a main conduit, a hollow needle projecting within the bore of said main conduit, said needle having a small opening in line with said bore to pass thread through the hollow needle and bore, and means supplying air to the space between said needle and conduit to project said thread from the main conduit, said main conduit being substantially unrestricted from the discharge end of the needle to the discharge end of the main conduit.

6. In a loom, a projecting jet for projecting weft threads across the loom, a main conduit having a central chamber, an outer annular chamber surrounding said central chamber, a plurality of openings connecting said chambers, means for supplying the outer chamber with compressed air, a hollow needle disposed within said central chamber, said needle projecting within the bore of said main conduit, said needle having a small opening whose entire length is in line with said bore, whereby to pass thread straight through the hollow needle and bore, and whereby the air passing between said needle and conduit projects said thread.

15 7. In a loom, mechanism to form a shed, a lay beam, reeds carried by said lay beam, a breast beam, a jet projector at one end of said lay beam, a suction mouth at the other end of said lay beam, means for supplying substantially constant air pressure to said jet projector, and means for supplying substantially constant suction to said suction mouth, a weft measuring device comprising a continuously rotating measuring wheel, a presser wheel intermittently pressing against said measuring wheel, a thread brake, means for guiding weft thread through said brake and between said measuring and presser wheels and into said jet projector, a cutting device adjacent said breast beam, means synchronized with the loom for urging said presser and measuring wheels together and releasing said brake at times, and for moving said wheels apart and braking said weft thread at other times, whereby said jet projector projects the weft thread through said shed as the weft thread is measured by said measuring wheel, and said weft thread is severed when said lay beam approaches said breast beam.

30 8. In a loom, mechanism to form a shed, a lay beam, reeds carried by said lay beam, a breast beam, a jet projector on one end of said lay beam, a suction mouth on the other end of said lay beam, means for supplying substantially constant air pressure to said jet projector, means for supplying substantially constant suction to said suction mouth, a weft metering device mounted on a stationary part of the loom, said metering device comprising a continuously rotating measuring wheel, a presser wheel intermittently pressing against said measuring wheel, a thread brake, means for guiding weft thread through said brake and between said measuring and presser wheels and into said jet projector, a cutting device carried by said breast beam, means synchronized with the loom for urging said presser and measuring wheels together and releasing said brake at times, and for moving said wheels apart and braking said weft thread at other times, whereby said jet projector projects the weft thread through said shed as the weft thread is measured by said measuring wheel, and said weft thread is severed when said lay beam approaches said breast beam.

35 9. In a loom, means for forming a shed, a device for projecting a weft thread through the shed, a metering device for feeding predetermined lengths of weft thread to said projection device, said metering device comprising a drive shaft, a measuring wheel and a pinion on said drive shaft, an auxiliary shaft, a gear on said auxiliary shaft meshing said pinion, a timing collar having a notch and journaled on said auxiliary shaft, a clutch between said collar and said gear, a control lever having a finger engageable in said notch, a pivot for said control lever, 40 a brake element over which weft thread passes,

a brake shoe operated by said control lever and engageable with said brake element to brake said weft thread, means urging said lever finger into said notch, a presser wheel adjacent said measuring wheel, a presser arm on which said presser wheel is journaled, a pivot for said presser arm, said presser arm having an extension engaging over a foot attached to said control lever, a spring operating between said control lever and said extension, and means operating said control lever to remove said finger from said notch.

10. In a loom, means for forming a shed, a pneumatic device for projecting a weft thread through the shed, a metering device for feeding predetermined lengths of weft thread to said pneumatic projection device, said metering device comprising a drive shaft, a measuring wheel and a pinion on said drive shaft, said measuring wheel having a relatively soft tire, an auxiliary shaft, a gear on said auxiliary shaft meshing said pinion, a timing collar having a notch and journaled on said auxiliary shaft, a friction clutch between said collar and said gear, a control lever having a finger engageable in said notch, a pivot for said control lever, a brake pin over which weft thread passes, a brake shoe secured to said control lever and engageable with said brake pin to brake said weft thread, spring means urging said lever finger into said notch, a presser wheel adjacent said measuring wheel, a presser arm on which said presser wheel is journaled, a pivot for said presser arm, said presser arm having an extension engaging over a foot attached to said control lever, a second spring operating between said control lever and said extension, a solenoid having a plunger, and a latch member pivoted to said plunger and having a catch projection engaging over said control lever.

11. In a loom, mechanism to form a shed, a pneumatic weft projecting device, a weft metering device comprising a continuously rotating measuring wheel, a presser member intermittently pressing the weft thread against the measuring wheel, means synchronized with the loom for causing said presser member to press the weft thread against the measuring wheel at a time when the shed is open and for holding said weft thread against the measuring wheel until a predetermined length of thread is pneumatically projected through the shed, said weft metering

device paying out the thread at a speed slower than that at which said weft projecting device tends to project the thread.

5 12. In a loom, mechanism to form a shed, a jet projector at one end of said shed, a suction mouth at the other end of said shed, means for supplying substantially constant pneumatic pressure to said jet projector, means for supplying substantially constant suction to said suction mouth, a metering device for paying out weft thread into said jet projector, said jet projector delivering the weft thread through said shed into the influence of said suction mouth, said metering device paying out thread, while the thread is 15 passing through the shed, at a speed which is slower than the speed at which said jet projector tends to project the thread, said metering device paying out said thread until the thread is projected substantially completely across the width of the cloth and is drawn taut by said suction mouth.

13. In a loom, mechanism to form a shed, a pneumatic projector for projecting weft thread through said shed, a metering device for paying out weft thread to said projector, said metering device paying out the thread at a speed slower than the projector tends to project the thread, said metering device thus exercising a hold-back control on said thread while it is being projected through the shed, until the thread is projected substantially completely across the width of the cloth.

GEORGE W. DUNHAM.
